CONCRETE GRAVE BOX

Filed Oct. 1, 1927

Inventor

Henry J. Lotz

P. D. Elliott

Attorney

UNITED STATES PATENT OFFICE.

HENRY J. LOTZ, OF MCKENNA, WASHINGTON.

CONCRETE GRAVE BOX.

Application filed October 1, 1927. Serial No. 223,326.

My invention relates to the outer box used in graves and adapted to receive the casket and its outer wooden box. The objects of my invention are, first, to provide such an outer 5 grave box which is made of concrete and yet which is of comparatively light construction; second, to provide a novel means for sealing the cover of said box to the box, whereby the joint will be as complete a protection for the 10 contents as the box itself; third, to provide a novel means of impressing the name and other data on the cover of the box; and fourth, to provide a box which is easy and cheap to make, substantially indestructible, and which 15 shall effectively protect the contents.

Further objects are, first, to provide a sealing means which is already prepared for use before it is applied and which only has to be laid in place and dampened, just before the 20 cover is lowered thereon, to effectively seal the box; second, to provide such a sealing means which can be prepared a long time before it is used without deterioration, which can be handled as a separate body before it is used, 25 and which can be made of indefinite length and from which the required length can be cut; and third, to provide such a sealing means which is cheap to make and to prepare and easy to apply.

Further objects are, first, to provide a cover 30 which may be cast a long time before its use and which, therefore, has no name or other data thereon, and whereon a portion is prepared to subsequently receive another cement 35 grouting in which the names and data may be impressed, or otherwise formed, while the grouting is plastic or green and just before the 40 cover is lowered on the box; and second, to provide means whereby the additional grouting will be held in its place in the cover and become, subsequently, substantially integral therewith.

I attain these and other objects by the devices and arrangements illustrated in the accompanying drawings, in which—

Fig. 1 is a perspective view of my improved 45 concrete grave box, showing a corner thereof broken away to reveal the interior and its construction; Fig. 2 is a perspective view of the sealing device before it is placed in use; and Fig. 3 is a section of a portion of my improved 50 concrete grave box, showing the joint between the side thereof and the cover, the seal in the said joint, the means formed in the cover to receive and retain the plastic grouting 55 in place therein and showing a portion of

a name impressed in said grouting, and a corner of the wooden outer box for the casket; and Fig. 4 is a perspective view of the under- 60 side of the name-protective cover.

Similar numerals of reference refer to similar parts throughout the several views.

The burial casket is usually enclosed in an outer wooden box 1, which is first placed in the grave, and into which the casket is lowered 65 after the funeral. In my invention this outer box 1 may, or may not, be used, but I have shown it in the drawings. The concrete box, comprising my invention, is a monolithic casting of concrete, having four side walls 2 and a 70 bottom 3, all with a heavy reenforcing wire 4, of fairly large mesh, embedded therein. This box is cast in any desired manner and is provided with a continuous groove 5, preferably 75 semicircular in section, as shown in Fig. 3, extending entirely around the upper edge of the side walls 2. The box, thus formed, is made large enough to easily hold the wooden box 1, or the casket, and may preferably be made in a limited number of sizes, as experience 80 may dictate. These boxes may be made in advance of their use and may be stored until required, as they do not deteriorate with the passage of time. The walls 2 and 3 are preferably made quite thin, about 85 one-and-a-half inches being the preferred thickness, and therefore the box is comparatively light in weight, this lightweight construction being made possible by the reenforcing of the wire mesh 4. The walls however 90 being of ample strength to properly protect the casket.

A slab or cover 6 is made in similar manner and weight, and is also reinforced by the wire mesh 4. This cover 6 is preferably a 95 straight slab, without groove or projection on its under side and is adapted to lie flat on the top edges of the four walls 2. In order to seal the connection between the slab 6 and the walls 2, and in order to secure them together and to render the two pieces into a substantially integral and single casting, as time passes, I insert the following described sealing means in the groove 5, before the top slab 6 is lowered thereon.

Referring to Fig. 2 it will be seen that I have provided a long continuous casing 7 of thin fabric, such as cheese cloth, sewed together along its edges, as at 8, to form a bag or tube which I fill with dry Portland 110 cement 14. This tube 7 may be made of any length desired and may be prepared in ad-

vance and stored away in a dry place for a reasonable time. The fabric of which the tube is made is preferably of very loose texture or mesh, and the sewing 8 is of wide stitching. When it is desired to use the seal, a sufficient length of the tubing is cut off therefrom and the ends thereof tied, or otherwise closed, to keep the cement 14 from spilling out therefrom. When the concrete grave box is to be sealed, the said length of tubing 7 is laid in the groove 5 in the walls thereof, with its ends open, and is then sprinkled with water, which it immediately absorbs. The diameter of the tubing 7, when full of cement, is preferably about the same as the diameter of the semicircular groove 5 and therefore the tubing fits neatly therein and extends upward, out of the groove, about one-half of its diameter. As soon as the tubing has been properly placed and wetted, the cover or slab 6 is lowered thereon and rests on the tubing and, since both the fabric and the sewing is open and readily split, the weight of the slab 6 bursts it apart forcing the cement 14 therefrom into the space between the upper end of the walls 2 and the cover 6. Thus the wet cement begins at once to form an impervious seal between the box and the cover, which seal soon becomes as hard as the concrete of the said parts and becomes substantially integral therewith as it enters somewhat into both the contiguous surfaces.

The slab 6, when first cast, is provided with a depression 9 (Fig. 3) on its upper surface near one end thereof, said depression being of such uniform depth as is convenient, and may well be of about one-half inch depth, and is provided with counter-sunk sides 10. When the name and data, which are to be applied to the box, are known this depression 9 is filled with wet cement grouting 11, to a level slightly above the surface of the slab 6, and then the letters and figures composing the name and other data are impressed in the green grouting by any suitable apparatus, such as that described in my application for patent for block-letter holders, filed under Serial Number 210,246, on August 3rd, 1927, as indicated by the depressions 12 in the grouting 11. This grouting is protected by a concrete cover 13 (Fig. 4) which is hollowed

out to cover the grouting 11, without touching it. The said cover 13 is laid on the box cover 6, over the grouting 11, after the cover 6 has been sealed on the box, as above described, and before the grave is filled. It effectively protects the green and still plastic grouting from being damaged by the earth thrown thereon when the grave is filled.

Thus it will be seen that I have devised a concrete grave box, of light construction, which may be prepared a long time in advance of its use, and adapted to receive a suitable plastic grouting just before it is to be used, in which the name, etc., may be impressed; and also a suitable sealing means which may also be prepared in advance of its use and handled without spilling its contents, and which may be applied to form the seal immediately before the cover of the box is lowered thereon, and which is broken open by the weight of the said cover when so placed in position.

Having therefore described my invention, what I claim is:—

1. A joint for concrete grave boxes comprising a loose mesh fabric tube containing cement, adapted to be laid between the upper edge of the box walls and the lower surface of a flat box cover, and to be dampened, whereby the weight of a flat cover will force the cement from the fabric tube and into contact with the box and its cover to form a binder and seal therefor. 75

2. A joint for concrete grave boxes comprising a loose mesh fabric tube containing cement and adapted to be dampened and laid in a groove extending around the upper surface of the walls of the box, and extending out therefrom, whereby when a flat cover is laid thereon the weight thereof will force the cement from said fabric tube and into contact with the box and its cover to form a binder and seal therefor. 85

3. The art of sealing concrete grave boxes, comprising forming a sealing tube of light fabric; filling said tube with cement; applying the tube to one surface to be sealed; wetting said tube; and applying the other surface to be sealed to said wetted tube, whereby the cement material is forced therefrom to form a binder and seal for the two said surfaces. 95 100
